Primary Examiner — Prabhakar Deshmukh(74) *Attorney, Agent, or Firm* — Wong, Cabello, Lutsch, Rutherford & Bruculeri, LLP(57) **CLAIM**

The ornamental design for a speakerphone peripheral, as shown and described.

DESCRIPTION

FIG. 1 is a perspective view of a speakerphone peripheral showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines showing in FIG. 1 and FIGS. 3 through 7 indicate disclaimed portions and form no part of the claimed design. It is understood that the grids of circular apertures schematically depicted in the drawings are continuous throughout the surfaces on which the apertures are shown.
